UNITED STATES PATENT OFFICE

169,263

ROLLER SKATE

Joseph Korba, Jr., Minneapolis, Minn., assignor
to Heiser Skate Company, Minneapolis, Minn.,
a corporation of Minnesota

Application July 16, 1951, Serial No. 15,890

Term of patent 7 years

(Cl. D34—14)

To all whom it may concern:

Be it known that I, Joseph Korba, Jr., a citizen of the United States, residing at Minneapolis, in the county of Hennepin and State of Minnesota, have invented a new, original, and ornamental Design for a Roller Skate, of which the following is a specification, reference being had to the accompanying drawings, forming part thereof.

Referring to the drawings:

Fig. 1 is a top plan view of a roller skate, showing my new design;

Fig. 2 is a bottom plan view;

Fig. 3 is a view in side elevation—opposite sides being identical;

Fig. 4 is a view in front elevation; and

Fig. 5 is a view in rear elevation.
The dominant features of my invention reside in those portions illustrated by full lines.

I claim:

The ornamental design for a roller skate, as shown and described.

JOSEPH KORBA, JR.
